Primary Examiner — Kevin Rudzinski*Assistant Examiner* — Sean D Lough(74) *Attorney, Agent, or Firm* — Price Heneveld LLP(57) **CLAIM**

The ornamental design for a brake spider, as shown and described.

DESCRIPTION

FIG. 1 is a perspective view of a brake spider embodying the present invention;

FIG. 2 is a front elevational view of the brake spider;

FIG. 3 is a first side elevational view of the brake spider;

FIG. 4 is a second side elevational view of the brake spider;

FIG. 5 is a rear elevational view of the brake spider;

FIG. 6 is a top plan view of the brake spider; and,

FIG. 7 is a bottom plan view of the brake spider.

The broken lines shown in the figures are for purposes of illustrating portions of the brake spider that form no part of the claimed design.
